UNITED STATES PATENT OFFICE

2,662,051

CONVERSION OF HEAVY HYDROCARBONS

Harry Louis Pelzer, Ogden Dunes, Ind., assignor
to Sinclair Refining Company, New York, N. Y.,
a corporation of Maine

Application December 28, 1949, Serial No. 136,069

2 Claims. (Cl. 196—51)

1

This invention relates to improvements in the conversion of heavy hydrocarbon oils. More particularly, it relates to improvements in the economic utilization of heavy residua which to an undesired degree are the products of modern heavy oil distillation and cracking operations.

The disproportionate demand for light fuels as compared to heavy oils and fuels creates a severe disposal problem for the petroleum refinery. The heavy ends of crude oil contain substantial quantities of asphaltic and coke-forming materials which are left as end-products, in the form of asphalt, heavy residual fuel oil, or coke, of conventional operations such as vacuum distillation designed to strip out the maximum recoverable fraction of distillable hydrocarbons, cracking and coking. Compared to the demand for gasoline and distillate fuels the market for heavy residual fuels and bituminous solids is smaller and less flexible. Hence the refiner has a major problem in economic disposal of residual materials, and this problem is aggravated as the supply of residual materials is multiplied by increasing demand for the production of gasoline and distillate products.

I have now discovered an improved method for treating heavy oil stocks which accomplishes a reduction in residuum produced and which effects an increase in the ultimate yield of gasoline produced from a given crude oil in over-all refinery operation. My method is especially practical in the sense that it is flexible and readily adapted to modern refinery practices. I have found that if heavy oils are heated to cracking temperatures in a fired heater so as to control residence time below that producing substantial cracking and if the preheated stock is flashed in a tower under conditions of reduced partial pressure and minimum residence time, increased yields of gas oil useful as cracking feed stock and a surprisingly useful bottoms product result. I preheat the heavy oil stock, for example, to a temperature approximating 850° to 950° F. and hold the stock in the heater for a period of time, say two to fifteen minutes to develop incipient cracking, while limiting the per cent crack (in terms of production of 400° F. end-point gasoline and lighter) to below about 10 per cent. I flash the preheated stock into the tower under substantially atmospheric conditions but with a partial hydrocarbon pressure reduced by the presence of substantial quantities of steam.

I have found that when the so preheated stock is flashed under pressure conditions of approximately atmospheric up to about 10 p. s. i. g. in the

presence of steam in an amount approximating 10 to 25 per cent by weight on the feed that the character of the conversion reaction is substantially shifted from conventional methods of treating heavy stocks. A higher yield of heavy gas oil is produced as distillate in comparison to vacuum distillation or to coking. The total quantity of overhead products is increased compared to distillation methods, while the amount of thermally cracked gasoline and light gas is substantially reduced and the gas oil fraction increased compared to coking operations. The latter represents an ultimate economic advantage since the quality of thermal cracked gasoline produced by conventional conversion of heavy oils is usually low while my heavy gas oil product represents a useful charge stock to catalytic cracking operations so that the ultimate yield of good quality gasoline is increased. The gas oil product is less refractory than ordinary heavy cycle stocks as is shown by its U. O. P. characterization factor and ultimately produces gasoline of a quality beyond that of the incidental thermal gasoline produced in heavy oil conversion operations.

25 The nature of the bottoms product produced according to my invention represents one of its important advantages. The material is a high melting point brittle pitch or asphalt like material but may be readily handled as a liquid at temperatures above its melting point as under processing conditions. Thus, the pitch product is removed as liquid bottoms but upon cooling hardens to a brittle solid which can be readily pulverized without coking. It can be easily flaked from water cooled rolls and as flakes or lumps can be readily ground in a ball mill, burr mill, or the like. The pitch is pulverized readily in a hammer mill and is suitable for use as pulverized boiler fuel either alone or mixed with coal.

30 The invention will be better understood by reference to the accompanying drawings which represent conventionally and schematically a simplified flow plan of my process in Figure 1 and a combination process with a fluid catalyst cracking unit in Figure 2.

35 In Figure 1 a heavy feed stock is charged by means of line 10 and pump 11 to vertical tube type heater 12. In the heater the stock is raised to a temperature approximating 850° to 950° F. and is held for a time sufficient to hold cracking below about 10 per cent, depending upon the nature of the pitch product desired while avoiding coking. The feed is introduced to pitching tower 13 through line 14, at a tower pressure of 50 atmospheric or slightly above. If pressure is held

on heater 12, a pressure reducing valve is provided in line 14. Saturated steam at about 212° to 300° F. is introduced to the bottom of tower 13 through line 15. Although I have shown a straight sided pitching tower, the lower portion of the tower may have a smaller diameter than the upper. Steam is introduced in an amount approximating 10 to 25 per cent weight on the feed depending on the nature of the pitch product desired. Increasing the amount of steam or the flash temperature or the time factor in the heater increases the melting point of the pitch product while decreasing yield. The steam input cools the bottom of the tower and reduces the flash temperature to about 790° to 850° F. At the same time the introduction of steam reduces the partial hydrocarbon pressure within the tower, minimizing tower residence time. If desired, process steam or water may be introduced with the oil to the heater coils. I have found that process steam also reduces oil partial pressure in the flash section and residence time in the coils, while increasing overhead gas oil and decreasing per cent crack.

The pitching tower as shown is advantageously divided by plate 16 into a lower flash section and an upper fractionating section. Bubble trays 17 are provided in the upper portion of the tower to improve fractionation and a partial condenser 18 which may be a water condenser or a heat exchange handling feed stock for preheat may be provided at the tower top. Lighter products are drawn from the upper portion of tower 13 through line 19, through condensing system 20 to receiving vessel 21. As shown receiver 21 has a restricted bottom section for water draw-off through line 22 while gas is taken off through line 23 and gasoline through line 24. A light gas oil fraction is advantageously taken from an upper tray of the tower as through line 25. A heavy gas oil fraction is taken from the bottom of the upper fractionating section of tower 13 as by line 26. Pitch product is withdrawn as bottoms through line 27 at a rate maintaining a dry tower or minimum liquid level. The lower flash section of the tower may be advantageously baffled so as to increase heat transfer between the charge oil and steam. We have found that it is important to maintain the boot of tower 13 below approximately 650° F. by steam introduction or other cooling means to prevent coking which would occur at higher temperatures in spite of operating with a dry tower. The maximum tower boot temperature of course varies with the residence time of the oil upon the boot wall and thus with the size of the unit.

The principles underlying my invention will be illustrated in the following example representative of a series of pilot plant runs of 8 to 45 hours duration on a small unit of the type shown in Figure 1. The feed to the unit comprised a virgin reduced crude having the following characteristics:

TABLE I

Gravity, °API	13.0
SUS, 210° F.	424.5
Extraction sediment	0.041
ATM U. G. I. coke	13.5
Vacuum U. G. I. coke	5.3
K (U. O. P. characterization factor)	11.37

This material was preheated to a temperature approximating 860° to 920° F. and was flashed into the pitching tower at a flash temperature ranging from about 810° to 850° F. The

tower top temperature range varied from 841° to 782° F. The quantity of process and stripping steam varied from 18.0 to 13.2 weight per cent on the feed. The tower bottom temperature maintained under these conditions varied between 597° and 670° F. The per cent crack in terms of weight per cent of 400° F. end-point material and lighter varied from 6.6 to 1.4 weight per cent on the feed. The yield of gas oil varied from 69.1 to 73.7 weight per cent while the yield of pitch varied from 19.7 to 27.4 weight per cent. The properties of the pitch produced varied with the yield obtained and the per cent crack on the feed stock. Pertinent data on six separate runs are tabulated below:

I found that it was advisable to use a hot overhead receiver on this unit in order to minimize emulsion difficulties in handling the overhead. By operating the primary or hot overhead receiver at 400° F. approximately 85 per cent of the heaviest hydrocarbons were condensed. The remaining 15 per cent of light hydrocarbons and the total water were readily separated in the secondary or cold overhead receiver.

I have found that pitch yield and quality is subject to flexibility in control by control of the per cent crack of the feed stock, the per cent steam or the flash temperature. With higher per cent crack, the pitch melting point is higher and the yield is reduced. The pitch, however, differs in quality from equivalent melting point pitch produced by increased steam quantities or flash temperatures in that the extraction sediment, for example, at the higher per cent crack is materially higher. A typical pitch produced according to the above example tested 266° F. (R & B) melting point and had a specific gravity of 1.1205 at 470° F. The molten pitch at this temperature was readily flaked to $\frac{1}{2}''$ x 2''-pieces of $\frac{3}{4}''$ -thickness on water cooled rolls. The flakes were quite brittle and could be ground to better than 50 per cent through 200-mesh.

The light and heavy gas oil from the above runs were composited and evaluated as a thermal cracking feed stock. This material is a very heavy long range gas oil which may be charged as such to a catalytic cracking unit. For thermal cracking the light and heavy gas oils should be handled separately or the composite material is advantageously rerun. The light gas oil produced in these runs was considered suitable as a TCC feed stock to a moving bed catalyst cracking unit such as the Thermofer system although the sulfur content due to the crude source was rather high. The quality of the gasoline produced was typical of thermal gasoline produced from the crude type.

A heavy cracked residuum can be handled similarly according to my invention but in this event

the gas oil recovered is most suitable as a fuel oil cutter stock. Where heavy oil disposal constitutes a serious economic problem, this method results in increased cracked cutter stock for blending off heavy bottoms while releasing an equivalent amount of acceptable cracking charge stock to gas oil cracking.

In either event, the pitch product has high softening point above about 250° F. (R & B) and usually about 300° F. (R & B) or more and is susceptible to flaking or pulverization in conventional equipment without caking or sticking. The heavy pitch is run as liquid from the unit to cooling belts or shaker drums for solidification and fragmentation. Slop pitch, melting below about 200 to 220° F. (R & B) is cut back with a cutter stock and sent to tankage. Advantageously, the molten pitch run from the unit is directly injected into an agitated water bath from which the fragmented particles are collected.

In Figure 2 a pitching unit charging a reduced crude or heavy tar and producing heavy gas oil cracking charge stock is illustrated in combination with a conventional fluid catalyst unit. The pitch feed comprises a heavy oil such as reduced crude or cracking still tar charged through line 100 in which may be mixed some cycle oil from the fluid catalyst unit through line 101. The feed is preheated in heater 102 and flashed to pitching tower 103. Steam is introduced to the boot of the tower through line 104 and overhead is removed by line 105. Pitch is removed from tower 103 by line 110. A heavy gas oil cut is withdrawn through line 106 and is charged with the fresh feed to the fluid catalyst cracking unit through line 107 to reactor riser 108. Regenerated catalyst is mixed with the fluid catalyst feed in line 108 from regenerator standpipe 109 and the mixture of charge oil and catalyst is discharged into reactor 111 through grid 112. A dense phase bed is maintained in reactor 111 from which spent catalyst drops into stripping well 113 where adherent oil is stripped from the catalyst by means of steam introduced through steam stripping equipment 114. Cracked products pass overhead from reactor 111 through nest of cyclones 115 through line 116 to fractionator 117. Catalyst particles carried over with the vapors are knocked out in cyclone 115 and returned to the dense phase bed through dip leg 118. From fractionator 117 gasoline and light gases are conventionally taken overhead by line 119. At least one cycle oil cut is withdrawn as through line 101 while heavy oil and catalyst sludge may be withdrawn through line 120. The stripped spent catalyst descending through stripping well 113 drops into reactor

standpipe 121 and thus into the foot of regenerator riser 122. Regenerating air is conventionally utilized as a carrier and introduced at 123 to carry the spent catalyst into regenerator 124 where carbon deposited on the catalyst is burned off so that the regenerated catalyst may be returned to the reactor through standpipe 109. Flue gases pass overhead through line 125 to a fines recovery system and stack (not shown).

My invention, therefore, provides a method for treating heavy hydrocarbon oils which is susceptible of flexible and continuous operation and which produces less residuum and that in a surprisingly attractive form. It produces more gas oil susceptible to cracking to valuable gasoline and light products in conventional thermal or catalyst cracking systems, and may be advantageously combined with existing units as a feed stock preparation unit for handling oils too heavy to process economically in catalyst cracking systems inherently limited to a narrow range of clean stocks or limited by regenerator design capacities.

I claim:

1. A process for treating heavy hydrocarbon oils which comprises preheating the charge oil to an incipient cracking temperature of about 850° F. to 950° F. for about 2 to 15 minutes and limiting the percent crack to below about 10 percent based on 400° F. and point gasoline and lighter materials, flashing the preheated charge in a tower maintained at a pressure of atmospheric to about 10 p. s. i. g., reducing the temperature within the flash zone to about 790° F. to 850° F. by introduction into the tower of about 10 to 25 weight percent of steam having a temperature from about 212° to 300° F., and removing vaporized materials and bottoms from the flash tower.

2. The method of claim 1 in which the flash tower bottom temperature is maintained at less than about 650° F. by the introduction of the steam having a temperature from about 212° to 300° F. into the lower portion of the flash tower.
